UNITED STATES PATENT OFFICE.

GEORGE P. WIGGINTON, OF KALAMAZOO, MICHIGAN, ASSIGNOR TO KALAMAZOO LOOSE LEAF BINDER CO., OF KALAMAZOO, MICHIGAN.

TEMPORARY BINDER.

1,241,802.

Specification of Letters Patent. Patented Oct. 2, 1917.

Application filed February 14, 1916. Serial No. 78,250.

To all whom it may concern:

Be it known that I, GEORGE P. WIGGINTON, a citizen of the United States, residing at Kalamazoo, in the county of Kalamazoo 5 and State of Michigan, have invented certain new and useful Improvements in Temporary Binders, of the which the following is a specification.

This invention relates to improvements in 10 temporary binders.

The main objects of this invention are:

First, to provide in a temporary binder or loose sheet holder an improved adjusting mechanism.

15 Second, to provide an improved temporary binder or loose sheet holder which is capable of rapid manipulation to permit removal of the sheets, and one which is very secure when adjusted, and simple and compact so that it may be readily embodied in a small binder although well adapted for use in larger binders.

20 Further objects, and objects relating to details and economies of construction and 25 operation will definitely appear from the detailed description to follow.

I accomplish the objects of my invention by the devices and means described in the following specification. The invention is 30 clearly defined and pointed out in the claims.

A structure which is a preferred embodiment of my invention is clearly illustrated in the accompanying drawing forming a 35 part of this specification, in which:

Figure I is a detail inside plan view of a binder embodying the features of my invention with the covers extended, the leaves being shown in an upright position.

40 Fig. II is a detail inverted view of the adjusting mechanism of the embodiment shown in Fig. I.

Fig. III is an enlarged detail section on a line corresponding to line 3—3 of Figs. I 45 and II.

Fig. IV is an inverted detail view corresponding to that of Fig. II, of a slightly modified embodiment of my invention, a single clutch lever being shown instead of 50 the clutch lever shown in Fig. II.

Fig. V is a detail inside view of still another embodiment or modification of my invention.

Fig. VI is a detail inverted view of the

adjusting mechanism of the embodiment 55 shown in Fig. V.

Fig. VII is a plan view of the adjusting lever clutch pawl of the mechanism shown in Fig. VI.

Fig. VIII is a detail longitudinal section 60 on a line corresponding to line 8—8 of Fig. VII.

Fig. IX is an inverted detail view of another modification or embodiment of my 65 invention.

Fig. X is a detail section on a line corresponding to line 10—10 of Fig. IX.

Fig. XI is an inverted detail view of still another modification or embodiment of my 70 invention.

In the drawing, similar reference characters refer to similar parts throughout the several views, and the sectional views are taken looking in the direction of the little arrows at the ends of the section lines. 75

Referring to the drawing, the covers 1 and 2 are preferably provided with clamping bars 3 substantially as shown in my Patent No. 1,022,452, issued April 9, 1912. The binder members 4 are preferably in the 80 form of flexible strips and extend between the covers, being connected to the cover 1 at 5 and to the cover 2 through my improved adjusting mechanism.

The cover 2 is provided with a recess or 85 chamber 6 in which the adjusting mechanism is disposed. This adjusting mechanism comprises a cross-head or member 7 slidably mounted on the bar 8 disposed longitudinally of the recessed cover. This 90 adjusting member is retained in its adjusted position on the bar 8 by means of the clutches 9. These clutches are lever-like in form and are mounted on the pivots 10 on the under side of the adjusting member to 95 coact with the bar 8, the clutches having holes 11 therein of such size that when the clutches are swung forwardly the clutches slide freely on the rod and when swung rearwardly they have a clutching engagement therewith effectively holding the adjusting member against inward movement, that is, movement toward the inner end of the cover, but permitting its outward movement without disengaging the clutches. 100

In the embodiment shown in Figs. I, II and III, I provide a pair of clutches disposed oppositely with their ends projecting

at the inner edge of the adjusting member so as to be grasped simultaneously with the grasping of the adjusting member. The clutches are automatically actuated to their engaging positions by means of the springs 11 mounted on the pins 12 with their free arms engaging the clutches at the outer sides of the clutch pivots. I preferably provide stops 13 against which the clutches rest when in their disengaged position.

In the modification shown in Fig. IV a single clutch only is shown. This is quite satisfactory. The double clutch merely provides additional security and divides the stress which would otherwise be carried by the single clutch.

In the modification shown in Fig. V the rod or bar 14 is connected to a cross bar 15 to which the binding members 4 are in turn connected. The bar 14 is supported for longitudinal movement on the cross piece or support 16 mounted on the cover 2. A clutch 9 is mounted on this support 16 to coact with the bar substantially the same as the clutch in the structures described. The clutch engaging movement, however, is toward the inner end of the cover, while the clutch engaging movement of the structure shown in Figs. I to IV is toward the outer end of the cover, the structure shown in Fig. V being substantially a reversal of the parts of the structure shown in Fig. I.

In the modified structure shown in Fig. V, I employ means for applying stress to the binding means. This comprises a lever 17 pivoted at 18 and provided with a clutch pawl 19 coacting with the bar 14. This clutch pawl is pivoted on the lever at 20 and provided with a slot 21 through which the bar extends. The outer end of the lever is disposed through the segmental slot 22, the ends of which constitute stops for the lever. When the lever is actuated the pawl clutches the rod 16 moving it toward the outer end of the cover. As the bar slides freely through the clutch 9 in this direction it is unnecessary to manipulate the clutch at the same time. On the return movement of the lever the clutch pawl automatically disengages from the bar, the upper end of the slot 21 being rounded so that it slips freely in the return direction. A light spring 23 insures the engagement of the clutch pawl.

A stop 24 is positioned so that the clutch pawl engages therewith when the lever is in its initial position thereby insuring the supporting of the clutch pawl in position to permit free adjustment of the bar without communicating its movement to the clutch lever. A spring 25 is mounted on the support 16 for returning and holding the clutch lever in its initial position.

In the modification shown in Figs. IX and X the clutch 26 is in the form of a

blade spring mounted on the block 27 so that its free end coacts with the bar. The lever 28 is pivoted at 29 to engage the clutch so that when the lever is actuated the clutch is disengaged. The lever is returned by the spring 30. A stop 31 is provided for the lever. The lever shown is a modification of one of the clutches.

In the modification shown in Fig. XI, the bar 8' upon which the adjusting member 8 is mounted is flat in cross section. The clutch member 32 is in the form of an eccentric pivoted at 33 to coact with the edge of the bar and provided with a finger piece or lever 34 disposed through a slot 35 in the adjusting member for convenience in manipulation. The clutch is thrown toward its engaging position by the spring 36 actuating substantially as the spring 11' in the embodiment shown in Fig. IV. The clutching movement of the clutch member 32 is away from the inner end of the cover so that stress applied to the adjusting member through the binding strips tends to cause a greater gripping or clutching action.

With the parts thus arranged I secure a structure which is very simple and secure in its adjustment. With the several modifications of my invention illustrated and described I believe that the application or adaptation thereof as described will be readily understood by those skilled in the art to which my invention relates.

Having thus described my invention, what I claim as new and desire to secure by Letters Patent, is:

1. In a temporary binder, the combination with the covers, of binding strips extending between the covers, a bar disposed longitudinally of one of the covers, an adjusting member to which said binding strips are connected slidably mounted on said bar, a pair of oppositely disposed lever-like clutches pivotally mounted on said adjusting member and having openings therein through which said bar is disposed, said clutches being positioned with their outer ends projecting at the edge of the adjusting member so that the clutches may be released and the adjusting member grasped simultaneously, springs mounted on said adjusting member for actuating said clutches to their engaging positions, and stops for said clutches when actuated to disengaged position.

2. In a temporary binder, the combination of a binding member, a bar, an adjusting member to which said binding member is connected adjustably associated with said bar, and a pair of oppositely disposed friction clutches pivotally mounted on said adjusting member to coact with said bar.

3. In a temporary binder, the combination with the covers, and a binding strip

extending between the covers, of an adjusting means carried by one of the covers and comprising a bar, and a pivoted friction clutch coacting with said bar.

5 4. In a temporary binder, the combination with the covers, and a binding strip extending between the covers, of an adjusting means carried by one of the covers and comprising a bar, and a spring actuated 10 friction clutch coacting with said bar.

5. In a binder, the combination with the covers and a binding strip extending between the covers, of a bar disposed longitudinally of one of the covers, an adjusting 15 member to which said binding strip is connected slidably mounted on said bar, a lever-like clutch pivotally mounted on said adjusting member and having an opening

therein through which said bar is disposed, said clutch being positioned with its outer 20 end projecting at the inner edge of the adjusting member so that the clutch may be released and the adjusting member grasped simultaneously, a spring mounted on said adjusting member for actuating said clutch 25 to its engaging position, and a stop for said clutch when actuated to disengaged position.

In witness whereof, I have hereunto set my hand and seal in the presence of two 30 witnesses.

GEORGE P. WIGGINTON. [L.S.]
